UNITED STATES PATENT OFFICE.

STEPHEN H. EMMENS, OF LONDON, ENGLAND.

SHELL FOR ORDNANCE.

SPECIFICATION forming part of Letters Patent No. 415,707, dated November 26, 1889.

Application filed January 11, 1889. Serial No. 298,047. (No model.)

To all whom it may concern:

Be it known that I, STEPHEN HENRY EMMENS, a subject of the Queen of Great Britain and Ireland, and a resident of London, in England, temporarily residing at Harrison, in the State of New York, have invented a new and useful Improvement in Artillery-Projectiles, of which the following is a specification.

This invention consists in certain novel features of construction and combinations of parts, hereinafter set forth and claimed, which are embodied in improved explosive projectiles for ordinary artillery.

The objects of the present invention are, first, to adapt hollow projectiles to be more readily loaded with initial and main charges of high explosives, together with a fuse or fuses for igniting the former; secondly, to facilitate access to the interior of such projectiles, as for adjusting sensitive fuses both in front and in rear of an initial bursting-charge; thirdly, to provide the projectile with a self-firing time-fuse of superior simplicity; fourthly, to provide for charging the heads of common and shrapnel shells with combustible or suffocating substances, and, fifthly, to form an efficient gas-check suitable for muzzle-loaders, in connection with an extended, lightened, and cushioned base.

Two sheets of drawings accompany this specification as part thereof. Figure 1 of the drawings represents an axial longitudinal section of an improved "common" projectile for muzzle-loading artillery; and Figs. 2, 3, and 4 represent cross-sections on the lines correspondingly numbered through the head, body, and base of the same, respectively. Fig. 5, Sheet 2, represents an axial longitudinal section of an improved shrapnel projectile for muzzle-loading artillery embodying the same invention in part. Fig. 6 represents a cross-section on the line 6 6, Fig. 5. Fig. 7 represents a sectional plan view in the two planes indicated by the line 7 7, Fig. 5, and Fig. 8 represents a fragmentary side elevation showing the external construction of the metallic main portion of the base.

Like letters of reference indicate corresponding parts in the several figures.

In each of the two improved projectiles represented by the drawings the head A screws on the body B by means of a project-

ing lip C, and is provided with a central bore D and sockets E, a foremost portion F constituting a removable ring, which screws on 55 a central nipple D', through which said bore D extends and allows access to said sockets E.

The sockets E may be filled with wood, lead, or iron for the purpose of adjusting the center of gravity of the projectile, or with bottles of a combustible fluid or fluids—such as a solution of phosphorus in bisulphide of carbon—or a fluid or fluids capable of giving off suffocating or blinding vapors, such as nitro-chloroform.

The body B is in each case constructed with powder-chambers E² for a divided main charge, separated by radial partitions integral with the walls of the body, as shown in Figs. 3 and 7, and with a central tube H, the 70 bore of which is in line with said head-bore D.

The base G of each of the projectiles extends rearwardly in the form of an externally shouldered, serrated, and grooved wall I, Figs. 1, 4, 5, and 8, stiffened by internal radial ribs 75 J, and filled with wood packing K, which precludes the gases of the propelling-charge of the gun from bursting open the wall I, and acts as a cushion to receive the first shock of the discharge. It also conveniently receives 80 wood-screws L, for attaching a cup-shaped gas-check I and a rear wad M. The packing itself is held in place and the gas-check is further attached by a central bolt N, screwing into the rear end of a central nipple O', which 85 may constitute the head of a base-plug O, as shown in Fig. 1, or may be integral with the base G, as shown in Fig. 5. In each of the said improved projectiles a self-firing time-fuse T occupies said head-bore D, and communicates with a cartridge E', of emmensite or other high explosive, placed within said tube H, and constituting an initial bursting or igniting charge to fire the main charge in the chambers E². Said time-fuse comprises 90 a protruding head z, formed on a metallic tube y, which is tightly fitted to said bore D, and has an internal shoulder near its rear end. This shoulder supports the head of a rim-fire primer x, the open end of which projects rearwardly through the contracted bore of the tube and is coupled to one end of a piece of ordinary safety-fuse w of the proper length, the other end of which leads to a det-

onator *v* in contact with said cartridge *E'*. A plunger *u* slides freely within the main bore of said tube *y*, and has a contracted and cupped rear end, (best seen in Fig. 5,) which is kept from contact with the rim of the primer *x* by a spiral spring *t*, interposed between its shoulder and that of the tube. A cross-pin *p*, occupying a hole in said head *z* and a groove or open slot in the end of the plunger *u*, prevents the accidental escape of the plunger without obstructing its effective inward movement. (Compare Figs. 1 and 5.) When the gun is fired, the inertia of the plunger *u* causes it to strike back and explode the primer *x*, which fires the safety-fuse *w*, and this, at the end of the time fixed by its length, explodes the detonator *v*, and thereby fires the cartridge *E'*, which in turn fires the main charge. In the projectile represented by Figs. 1 to 4, inclusive, said detonator *v* is applied directly to the safety-fuse *w*. The time-fuse is conveniently confined to said head-bore *D*, and a percussion-fuse *P*, Fig. 1, is arranged behind the cartridge *E'* within the long bore of the central tube *II*, the latter, together with said powder-chambers *E*², extending from end to end of the body *B*, minus the length of a lip *C*², by which it is screwed to its base *G*. The supplemental screw-joint at this point may facilitate tightly filling the chambers *E*² with some high explosives, and serves peculiarly to facilitate so interposing the initial charge between two distinct firing-fuses by the location of a percussion-fuse within the rear end of the tube *II*.

The particular percussion-fuse *P* represented in Fig. 1 comprises an outer metallic tube *a*, which is screwed on the reduced front end *b* of the base-plug *O* of this projectile. The front end of the tube *a* is provided with a suitably-charged detonating-chamber *c*, and with a hollow anvil-piece *d*, extending rearwardly and carrying a primer *e*. A striker *f*, of conical outline in front, is held at the rear end of the space within the tube *a* by the pressure of spring-fingers *g*, attached within a hollow leaden cylinder *h*, which is in turn kept thereby in the front end of said space within the tube *a* until the gun is fired, when the inertia of the cylinder *h* causes it to slip backward on the point of the striker *f*. The spring-fingers *g* then engage beneath a circumferential shoulder *i* formed on said point, so that when the onward course of the projectile is arrested the striker, weighted by the leaden cylinder, flies forward and explodes the primer *e*, and thus fires the detonating-charge within the chamber *c*, which explodes the cartridge *E'* if the time-fuse has not already exploded the whole.

The powder-chambers *E*² may be provided with cushioning-wads *W*, Fig. 1, of wood or the like, and may be covered at one or both ends with gaskets *V*, of leather or the like, in customary manner.

In the shrapnel projectile, Figs. 5 to 9, inclusive, a very small initial cartridge *E'* suf-

fices. This is located within the tube *II* at the rear end of the body *B*, and a piece of quick fuse *q* is interposed between the safety-fuse *w* and the detonator *v*, the fuses *w* and *q* being securely coupled by a ferrule *r*. The small powder-chambers *E*² of this projectile are closed in front by a rigid loose diaphragm *X*, which is held against a shoulder *Y* within the body *B* by a shouldered central tube *Z*, the front end of which occupies a counter-bore within the head *A*, the interior of the tube forming a continuation of that of said tube *II* and of the head-bore *D*. In front of the diaphragm *X* is a relatively large cylindrical bullet-chamber *S*, to be charged in the customary manner. The metallic main portion of the base *G* of this projectile, together with its internal nipple *O'*, is preferably made integral with the body *B*; otherwise the bases of both projectiles are alike. Said improved common projectile, Figs. 1 to 4, inclusive, is selected for my claims herein, which do not apply to both projectiles.

The internal construction of the base *G*, broadly considered, the peculiar construction of the percussion-fuse *P*, Fig. 1, and the combination of the latter with the initial cartridge *E'*, body *B*, and base-plug *O*, as illustrated by Figs. 1 and 3, are claimed in a companion specification of even date herewith, constituting part of application, Serial No. 296,048, filed January 11, 1889, and form no part of the present invention except in connection with other elements as hereinafter set forth.

Excepting the base *G*, as shown in Figs. 1, 4, 5, and 8, with its peculiarly-constructed gas-check and rear wad, the several features of my present invention may be embodied alternatively in projectiles for breech-loaders, and other like modifications will suggest themselves to those skilled in the art.

Having thus described said improved projectiles, I claim as my invention and desire to patent under this specification—

1. A projectile for artillery, having a cylindrical body provided with powder-chambers for a divided main charge separated by radial partitions integral with the walls of the body and with a central tube, and a head screwed on said body and having a bore aligned with said tube, said tube and bore accommodating an initial charge, and a fuse or fuses for firing the same, substantially as hereinbefore specified.

2. In combination with a cylindrical projectile body having radial partitions and an axial tube integral therewith, a base and a head attached to its respective ends by screw-joint, so as to be removable therefrom, substantially as hereinbefore specified.

3. In a projectile for artillery, the combination, with a cylindrical body containing an initial cartridge of high explosive and a head having a bore aligned with said cartridge, of a self-firing time-fuse comprising a headed and internally-shouldered tube fitted to said bore, a rim-fire primer, the open end of which

- protrudes from the rear end of said tube, an inertia-actuated plunger having a shouldered and cupped rear end, a spiral spring interposed between the shoulders of said tube and 5 plunger, a detonator in contact with the initial cartridge, and a piece of safety-fuse of the required length interposed between said primer and said detonator, substantially as hereinbefore specified.
- 10 4. In a projectile for artillery, the combination, with a body containing bursting charges and an axial fuse or fuses for firing the same, of a head having an axial fuse-bore and provided with cavities or sockets around 15 and parallel with said fuse-bore, and with a

removable annular cover common to such cavities or sockets, substantially as hereinbefore specified.

5. In a projectile for muzzle-loading artillery, the combination, with a rearwardly-extended hollow base filled with wood packing, and externally shouldered, serrated, and grooved, as shown, of a cup-shaped gas-check and a rear wad attached to said packing by wood-screws, substantially as hereinbefore 25 specified.
